UNITED STATES PATENT OFFICE.

MALCOLM H. BAKER, OF BRAINTREE, MASSACHUSETTS; MARIE H. BAKER, ADMINISTRATRIX OF SAID MALCOLM H. BAKER, DECEASED, ASSIGNOR, BY MESNE ASSIGNMENTS, TO TREMONT PRODUCTS COMPANY, A CORPORATION OF MASSACHUSETTS.

TIME-RETARDED LAMP-EXTINGUISHING DEVICE.

1,388,504.

Specification of Letters Patent. Patented Aug. 23, 1921.

Application filed August 9, 1915, Serial No. 44,602. Renewed November 4, 1920. Serial No. 421,792.

To all whom it may concern:

Be it known that I, MALCOLM H. BAKER, a citizen of the United States, and a resident of Braintree, in the county of Norfolk and 5 Commonwealth of Massachusetts, have invented certain new and useful Improvements in Time-Retarded Lamp-Extinguishing Devices, of which the following is a specification.

10 This invention relates to self-contained lamp governing apparatus, wherein is incorporated devices automatically operative to delay the actual extinguishment of the lamp for a substantial interval of time after the 15 manual actuation of the controlling apparatus that is designed to effect such extinguishment, such devices however being so arranged as to permit the lamp, when supplied with fuel and lighted, continually to 20 burn or operate in a normal manner until after said extinguishment-causing actuation.

Apparatus in general designed for a similar purpose is disclosed in my co-pending applications, Serial No. 17,805, filed Mar. 25 29, 1915, and Serial No. 23,991, filed April 26, 1915, wherein is employed thermo-dynamic devices arranged to be rendered slowly operative to cause such delayed lamp extinguishment through the time required 30 to raise said devices to an operative temperature after same are subjected to a substantially constant source of heat.

The present invention contemplates the use of a purely mechanical lamp-governing 35 apparatus for accomplishing the above described functions as distinguished from an apparatus incorporating thermo-dynamic devices for producing the desired interval of delay before lamp extinguishment; and an 40 apparatus which is readily applicable, preferably, in a self-contained structural form, to any of the common and conventional types of illuminating lamps, whether utilizing as a light producing fuel, gas, oil, or 45 electricity.

The invention has as its object, broadly, to meet the almost universal need for the continuance of light for a brief interval after the said light has been "turned off," it 50 being difficult to cite an instance where such continuance of light, for a period ranging from one to say three minutes, is not only

desirable as a matter of convenience but even as a preventive of accidents.

Not only in domestic use is such continuance desirable, but in commercial use as in factories, stores, or shops, it becomes of considerable importance, since it avoids the condition of groping in the dark on the part of the last person to leave such premises, and 60 becomes specifically convenient in cases where the last light to be put out is located at a distance from the exit.

I am well aware that many mechanical devices, such as time switches, clock attachments, and other devices exist for causing the extinguishment of a light at a predetermined hour, or for lighting the same at such hour, or for extinguishing a light a predetermined time after it has been turned on, 70 and that such devices as dash pots or liquid controlled means have been used which operate to extinguish the light a definite time after it has been turned on, but none of these meet the needs which my invention fulfills,— 75 which is, specifically, to provide means adapted to cause extinguishment of the light a definite time after actuation, and to actuate such means, not by the turning on of the light, but either by a reversal, or "turning off" action of the lighting means, or by 80 an equivalent thereof. This provides a lamp which is turned on and lighted in the usual manner, and which presents the usual "turning off" means,—but which further 85 provides means to retard the action of the said "turning off" means when the latter are operated. That is, a key, chain pull, or the equivalent is provided to turn on the lamp in the usual manner,—and means are 90 provided whereby, when the said key or a separate instrumentality is actuated to turn off the lamp, extinguishment is delayed for a brief period, say one to three minutes, sufficient to meet the purposes for which the invention is intended.

The purpose and operative principles that characterize a lamp extinguishing apparatus of the above described nature are entirely foreign to the numerous and well-known safety, fuel-cut-off devices that are 100 commonly applied to gas lamps for automatically stopping the flow of gas in case the burner flame be blown out or otherwise

accidentally extinguished. In such safety devices there is commonly employed a spring, or other power means, constantly tending to close the gas-supply valve and restrained from so acting while the lamp is normally burning, by a latch, brake, or other locking device that depends for its restraining action entirely on heat generated by the burner flame. In contrast to such devices it 5 is the purpose of my invention, to provide a lamp whose fuel supply is not necessarily dependent upon heat generated by the lamp, and that further incorporates retarded lamp extinguishing mechanism designed to be rendered operative for the purpose of extinguishing the lamp at a time when the lamp 10 is normally burning.

Specifically, herein, I make use of spring motor to extinguish the lamp, and retard 15 the action of such motor either by a fan retarded gear system, a dash pot device, or other retarding equivalents.

I have illustrated my invention in the annexed drawings, in which Figure 1 is an 20 elevation and Fig. 2 a plan, partially sectioned, of an ordinary fish tail gas burner provided with my retarded extinguishment means. Fig. 3 is an elevation of an electric light bulb similarly provided, and Fig. 4 25 again shows, in elevation, a gas burner in connection with extinguishing means of another type. Fig. 5 is a form modified from Fig. 4 and shown in elevation, and Fig. 6 illustrates my device adapted to an oil lamp 30 burner.

In the drawings, in Figs. 1 and 2, the flame of the burner appears (in Fig. 1 only) at 1 and the burner stem at 2. The usual taper valve 21, operating in a valve 35 casing 7, carries a disk 3 provided with a pin 6. An arm 5 is freely pivoted to the disk 3 and carries pull chains 8, 9, and also an auxiliary arm, or extension, 55. A train of gear wheels appears at 15 and a retarding fan at 16. A coiled spring is shown at 20.

Operation is as follows,—when the chain 40 is pulled the arm 5 swings, engages the pin 6 and rotates the disk 3 to open the valve. This disk is then locked in the open 45 position by the engagement of the slot 11 with the spring catch 12 and thus maintained open against the action of the coiled spring 20. During this action the toothed portion of the disk 3 has revolved the gear 50 wheel 18 and wound up the spring 20, the said wheel rotating freely with respect to the wheels 15 through the action of the pawl 17. The burner is now operated as 55 desired until it is desired to extinguish same. Then the chain 9 is pulled, which 60 swings back the arm 5 and brings the auxiliary arm 55 into engagement with the catch 12 thereby opening the same from engagement with the slot 11 and thus freeing

the disk 3. This disk is then rotated slowly to the closed position of the valve, the motion being retarded by the action of the gear train 15 and fan 16, which are now brought into action, to oppose the unwinding movement of the spring 20, by the engagement of the pawl 17 with the wheel 18. The arrangement of the holes in the valve and valve casing are such that a considerable closing movement of the said valve 70 takes place before the gas begins to be cut off. By this means a considerable time element is introduced between the actuation of the chain 8 and the extinguishment of the light. 75

In Fig. 3 the same arrangement of gear train is applied to an electric light bulb 26, a series connection with the said bulb being made from the contact 25, the contact 24, and the disk 3. In this device, when 80 the chain 8 is pulled the arm 5 engages the pin 6 of the disk 3, rotates the said disk, brings together the contacts 24, 25, and lights the lamp,—the disk 3 being locked in this position by engagement of the catch 85 13 with the slot 11 in the usual manner. The coiled spring 20 (not shown in the figure) has in the meantime been wound up precisely as in Fig. 1. To extinguish, the chain 9 is pulled, swinging back the 90 arm 5 and releasing the catch 13. The disk 3 is now rotated as before and against the retarding action of the fan 16 until the contact 24 has left the contact 25 when the lamp is extinguished. The length of bearing given to 25 of course determines the time interval elapsing before extinguishment. This figure, it is to be understood, is largely diagrammatic, so far as the electrical portions are concerned. 95

In Fig. 4, the chain 8, when pulled, rotates directly the disk 3 thus opening the valve and at the same time raising the dash pot plunger 29 (which is permitted to lift freely through the opening of the ball valve 110 28) as well as placing in tension the spring 32. The valve is locked open by the engagement of the catch arm 33, which is pivoted to the disk 3 at 35, with the fixed block 34. 100

To extinguish, the chain 9 is pulled, which frees the said catch 33 from 34 and thus permits the spring 32 to close the valve against the retarding action of the dash pot. In this case, also, the valve arrangement is 115 such as to permit considerable closing action of the valve stem before gas is cut off.

Fig. 5 shows a modification of Fig. 4 whereby the gas may be turned on or regulated as desired independent of the extinguishing means,—whereas in the former types the gas has been required to be turned full on. In this figure, the gas is turned on to any desired degree by means of the chain 8,—and a second chain might be pro- 120 125 130

vided to rotate the valve in the direction opposite to that caused by said chain 8 if desired, by which means the gas might be raised or lowered or immediately extinguished. When it is desired to extinguish with time interval, the chain 9 is pulled, which raises the plunger 29 of the dash pot 27 and at the same time energizes the spring 32. On releasing this chain 9, after the pull, the dash pot plunger slowly descends under the influence of the spring 32, and the catch 41, carried by the arm 40, reaches and engages the slot 11 of the disk 3, no matter at what position of rotation the said disk may happen to be set. When this engagement takes place, the disk 3 is of course also rotated and the valve closed. Suitable time interval is provided by giving considerable travel to the catch 41 before it engages with the slot 11.

In Fig. 6, the burner appears at 45 and the chain 9 is pulled to extinguish the lamp. This rotates the disk 50 and thereby the wheel 18 to wind up the coiled spring 20 (see Fig. 1) in the usual manner. On releasing the chain, the said spring unwinds in the usual manner, the action being retarded as before, (in Fig. 1) by the fan 16 through engagement of pawl 17 and gear train 15.

When the disk 50 is rotated the slot 54 therein engages the catch 49 pivoted at 48 to the arm 46, which arm is fulcrumed at 47 to the burner structure. On the reverse rotation of the disk 50 the end of the arm 46 is thrown over the flame 44 to extinguish same. As rotation continues the catch 49 leaves the slot 54, the arm 46 falls back out of extinction position with relation to the flame 44 through the action of excess weight to the left of fulcrum 47, and rotation is finally checked by engagement of slot 54 with catch 51. The lamp is now ready for re-lighting as may be desired.

A suitable time interval is secured by means of the travel distance given to the slot 54 before engagement is made with the catch 49.

It is evident that many other forms of mechanical retarding devices might be employed, in addition to the two general types herein illustrated, without departing from the spirit of my invention, which may be summarized as the introduction, by purely mechanical means in the present application, of a time interval between the actuation of the extinguishing mechanism of a lamp and the actual occurrence of extinction. Or, in other words, the introduction of retarding means into the operation of lamp extinction.

Of course the herein described means might be applied to dim, in place of extinguishing, a lamp, without departing from the spirit of the invention, and wherein, in

the claims, I have used the word "decrease" in connection with the light emitted by a lamp, this word is to be taken as covering any decrease down to and including total extinguishment.

Of course the means employed to turn on and turn off, or extinguish, lamps, vary with the different types of lamps. For example, with a gas lamp the actuation of the turning on means involves the opening of a valve, after which the gas is ignited in the usual manner. With an electric lamp the actuation of the turning on means results directly in the lighting of the lamp, while with an oil lamp the said actuation merely comprises the withdrawal of the extinguisher so as to leave the wick free for ignition. Similarly, the actuation of the extinguishing means involves the closing of a valve with gas lamps; the opening of a circuit, generally, with electric lamps; and the movement of the extinguisher with oil lamps.

It is of course also further evident that the actuation of the turning on means must be independent of the actuation of the extinguishing means;—that is, the turning on means must be adapted to be manually actuated and then released, after which the lamp must continue in normal operation, or in a condition for normal operation. In this respect the device illustrated is different from any lamp adapted to be automatically extinguished a predetermined time after being turned on.

Wherever, therefore, the terms "means to turn on the lamp" or "extinguishing means" occur they are to be taken in this broad sense, and not in the sense of being limited to a valve movement, or a switch movement.

Without, therefore, limiting myself to the precise forms shown herein, what I claim is,—

1. In combination with a gas burner and controlling valve therefor, means adapted upon designed manipulation to open the valve; actuating devices including a motor spring adapted to be energized, upon opening of the valve, to close the same; and mechanism arranged independently of the operation of said burner automatically to catch and to hold said devices inoperative for an indeterminate period after said valve is opened; said mechanism being separately actuatable by subsequent manipulation of said valve opening means thereby to free said devices for operation while the burner is normally operating; together with retarding means automatically operative to slow down the valve-closing action of said devices, thereby to delay burner extinguishment after said subsequent manipulation of said means.

2. A lamp, having self-contained within its structure, and in combination; a source of

- light; an element operatively related to said source of light and movable to different positions respectively to extinguish and to permit burning of the lamp; means normally operative irrespective of heat from the lamp to retain said element continuously in its position to permit burning of the lamp; a spring-urged actuator arranged during spring-urged movement to impel 5 said element to the latter's said extinguishing position; an impeding device connected to slow down the spring-urged movement of the actuator; a control extension adapted for manipulation to energize the actuator 10 spring; and mechanism arranged to cooperate with the spring-urged movement of said actuator and rendered operative through designed manipulation of said control extension to effect the removal of said 15 element from retention by said means.
3. In a lamp the combination with light controlling apparatus arranged independently of the burning of the lamp normally to permit indefinite continuation of said 20 burning; of normally idle automatically acting lamp extinguishing mechanism; retarding devices for slowing down the automatic action of said mechanism when the latter is set in motion; and control means arranged upon one movement to energize said 25 mechanism and hold the same inoperative; and upon a subsequent movement to release said mechanism and set the same in motion to extinguish the lamp.
- 30 4. In a self-contained gas burner and controlling valve arrangement, in combination; normally-inactive, automatic, spring-actuated, mechanism, including a retarding device connected to slow down the movement 35 thereof, operatively related to said valve to close the same; manually-operable means operatively arranged upon one control movement thereof to energize said mechanism, and to set said valve open for continuous 40 burner operation; and means automatically to hold said mechanism inoperative when so 45 energized; together with mechanical connection between said first means and said last means, whereby independent reverse movement of said first means is operative to release said mechanism to close the valve.
5. In a self-contained gas burner and controlling valve arrangement, in combination; normally-inactive, automatic mechanism, operatively related to the valve to close the 50 same, and comprising a spring-actuated element with mechanical retarding devices to slow down the movement thereof; a single, manually-operable member, operatively related both to said valve and to said mechanism, and adapted by a single control movement to energize said mechanism and to set said valve to permit continuous, undisturbed operation of the burner; and a spring-actuated catch positioned automatically normally to hold said mechanism inoperative when so energized, and arranged to be tripped by a reverse movement of said member, thereby to release the automatic valve-closing mechanism for action.
6. In a lamp, in combination; a source of light; an element movable between positions respectively to free and to cut off said source of light; a self-returnable actuator for said element having retarding devices to impede 55 automatic return movement thereof from a tensioned position and arranged during said return movement to impel said element to its cut-off position relative to the source of light; mechanism independent of lamp operation for holding said element retracted from its said cut off position when not impelled thereto by said actuator; and control instrumentalities arranged to energize and release said actuator for causing its self-return, while the lamp is normally burning.
- In witness whereof I have hereunto set my hand this 7th day of August, 1915.
